FRANK H. BLAKESLEE, OF CLEVELAND, OHIO, ASSIGNOR TO THE AJAX MANUFACTURING COMPANY, OF CLEVELAND, OHIO, A CORPORATION OF OHIO.

FEED MECHANISM.

1,260,305.

Specification of Letters Patent. Patented Mar. 26, 1918.

Application filed May 14, 1915. Serial No. 28,077.

To all whom it may concern:

Be it known that I, FRANK H. BLAKESLEE, a citizen of the United States, and a resident of Cleveland, county of Cuyahoga, and State of Ohio, have invented a new and useful Improvement in Feed Mechanism, of which the following is a specification, the principle of the invention being herein explained and the best mode in which I have contemplated applying that principle, so as to distinguish it from other inventions.

The present invention relates to a feed mechanism to be used in various connections and to be of particular value where it is desired to secure an intermittent feed for any given part of the mechanism without adding to the complication of the machinery by providing a reduced driving ratio for the feeding mechanism. While it is of no particular importance as to what machine I have adapted the present feeding mechanism, it may be stated, for illustration only, that it has been used for feeding bars of stock to forging machines. To the accomplishment of these and related ends said invention then consists of the means hereinafter fully described and particularly pointed out in the claims.

The annexed drawings and the following description set forth in detail certain mechanism embodying the invention, such disclosed means constituting, however, but one of various mechanical forms in which the principle of the invention may be used.

In said annexed drawings:—

Figure 1 is a plan view showing attachment of the present feeding mechanism to a forging machine designed for the manufacture of bolts, spikes and the like; and Fig. 2 is an end elevation of the feeding mechanism.

The general features of the forging machine 1 will not of course be described, as they are of no importance in this connection and I will only say that a link or lever 2 is attached to or operated by a main driving shaft 4 of the forging machine. This lever 2 is connected to one end of an arm 5 which is pivotally mounted, being rota-

table on a shaft 6 which bears one of a pair 50 of complementary rolls 7 for engaging the bar of stock 8 and introducing the same into the forging machine, the other of such pair of rolls being attached to a second parallel shaft which is inter-geared with the 55 first named shaft to provide for simultaneous operation.

Attached to the shaft 6 is a toothed wheel 9 which is adapted to be normally engaged by one of two similar pawls 10 which are 60 pivotally mounted upon a common axis in the form of a pin 11 and are provided with extensions 12 which are adapted to be contacted by the several faces of a cam 15 which is attached to a disk 16, the cam and 65 disk being mounted upon a suitable stub shaft 17 which is pivotally mounted in a fixed bearing 18 and a movable bearing 19 slidably upon two parallel rods 20, the movable bearing being normally pressed 70 against the fixed bearing with a considerable pressure by means of a spring 21 interposed between the movable bearing and a collar 22 which is attached to the two parallel rods. The cam 15 is provided for the 75 purpose of controlling the engagement of the pawls 10 with the toothed wheel and has, as shown, two spaced and parallel faces 13 which, when either engages the extensions of the pawls, are adapted to restrain 80 the same from engagement with the toothed wheel. Between such spaced and parallel faces on the cam are other faces 14 which are adapted to permit the engagement of the pawls with the toothed wheel. The arm 85 5 is oscillated by means of the lever 2 operated by the cam on the driving shaft and upon a forward movement of the arm one of the two pawls rotates the toothed wheel through a portion of the revolution, if at 90 that time the cam is in such a certain position that it permits the pawls to engage the wheel.

The disk 16 which is attached to the cam controls the movement of the same and is 95 provided with four equally spaced one-way notches 25 on its periphery, there being a fixed pawl 26, which is mounted, not upon

the arm, but upon some adjacent portion of the machine frame, which normally presses against the outside of such disk and drops into the notches when the latter are 5 in proper positions. The movement of the arm forward moves the disk past the fixed pawl. The disk is prevented from rotation on its axis by this movement by a pressure on the bearings of the shaft and such movement brings the next notch into position to 10 receive the engaging end of the fixed pawl, so that as the arm is swung back the fixed pawl prevents the disk from returning and the latter is moved through a quarter of a 15 revolution by the time the arm is returned to its initial position. This movement of the disk rotates the cam through a quarter of a revolution, so that upon the next succeeding forward movement of the arm the pawls 20 are held out of position with the toothed wheel and there is no feed. In this way an intermittent feeding of the toothed wheel forward is secured and without the necessity for introducing any reducing gearing 25 between the main driving shaft and the shaft which is to be rotated at such slower speed.

Either one or two pawls may of course be used and I use two for the reason that 30 in this case there is always one pawl engaging the toothed wheel preventing the same from slightly turning in either direction except when rotated by the feeding mechanism. The simplicity of the construction 35 of the latter mechanism and the positiveness of its operation will be evident from the foregoing description.

Other modes of applying the principle of 40 my invention may be employed instead of the one explained, change being made as regards the mechanism herein disclosed, provided the means stated by any of the following claims or the equivalent of such 45 stated means be employed.

I therefore particularly point out and distinctly claim as my invention:—

1. In feed mechanism, the combination 50 with a wheel to be rotated, of an oscillatory arm, a pawl pivotally mounted on said arm and normally engaging said wheel, a cam pivotally mounted on said arm and adapted, in one position, to retain said pawl from engagement with said wheel, and means adapted to intermittently rotate said cam.

2. In feed mechanism, the combination 55 with a wheel to be rotated, of an oscillatory arm, a pawl pivotally mounted on said arm and normally engaging said wheel, a cam pivotally mounted on said arm and adapted, in one position, to retain said pawl from engagement with said wheel, a disk attached to said cam, said disk being provided with four equally spaced notches, and a fixed pawl

adapted to engage in one of such notches upon forward oscillation of said arm and to rotate 6 said disk a quarter revolution upon the return oscillation of said arm.

3. In feed mechanism, the combination 70 with a wheel to be rotated, of an oscillatory arm, a pawl pivotally mounted on said arm and normally engaging said wheel, a cam pivotally mounted on said arm, said cam having two oppositely disposed faces adapted, when either engages said pawl, to retain the latter from engagement with said wheel, 75 and two other intermediate faces, adapted, when either engages said pawl, to permit the latter to engage said wheel, and means adapted to intermittently rotate said cam.

4. In feed mechanism, the combination 80 with a wheel to be rotated, of an oscillatory arm, a pawl pivotally mounted on said arm and normally engaging said wheel, a cam pivotally mounted on said arm, said cam having two oppositely disposed faces adapted 85 when either engages said pawl, to retain the latter from engagement with said wheel, and two other intermediate faces, adapted when either engages said pawl, to permit the latter to engage said wheel, a circular 90 disk attached to said cam, said disk being provided with four equally spaced notches on its periphery, and a fixed pawl adapted to normally rest upon said disk and to engage in such notches, thereby causing a quarter 95 turn of said disk upon each return oscillation of said arm.

5. In feed mechanism, the combination 100 with a wheel to be rotated, of an oscillatory arm, a pawl pivotally mounted on said arm and normally engaging said wheel, a cam pivotally mounted on said arm, said cam having two oppositely disposed faces adapted 105 when either engages said pawl, to retain the latter from engagement with said wheel, and two other intermediate faces, adapted, when either engages said pawl, to permit the latter to engage said wheel, a circular disk attached to said cam, said disk being provided with four equally spaced notches on its 110 periphery, and a fixed pawl adapted to normally rest upon said disk and to engage in such notches, thereby causing a quarter turn of said disk, upon each return oscillation of 115 said arm, and pressure bearings for said disk and cam adapted to tend to maintain the same from oscillation.

6. In feed mechanism, the combination 120 with a wheel to be rotated, of an oscillatory arm, two pawls pivotally mounted on said arm about the same axis, one of said pawls always engaging said wheel, a cam pivotally mounted on said arm, said cam having two oppositely disposed faces, adapted, when either engages said pawls, to retain the latter from operative engagement with said 125

wheel, and two other intermediate faces adapted, when either engages said pawl, to permit the latter to engage said wheel, a circular disk attached to said cam, said disk being provided with four equally spaced notches on its periphery, and a fixed pawl adapted to normally rest upon such disk and engage in said notches, thereby causing a quarter turn of said disk upon each re-

turn oscillation of said arm, and pressure ¹⁰ bearings for said disk and said cam adapted to tend to maintain the same from oscillation.

Signed by me, this 13th day of May, 1915.
FRANK H. BLAKESLEE.
